UNITED STATES PATENT OFFICE.

THORWALD GOSERND, OF STURGEON BAY, WISCONSIN.

DRILL.

SPECIFICATION forming part of Letters Patent No. 394,169, dated December 11, 1888.

Application filed September 21, 1888. Serial No. 285,981. (No model.)

To all whom it may concern:

Be it known that I, THORWALD GOSERND, a citizen of the United States, residing at Sturgeon Bay, in the county of Door and State of Wisconsin, have invented a new and useful Improvement in Drills, of which the following is a specification.

The object of this invention is to provide a simple, cheap, strong, and durable drill, which may be used either for drilling in wood or iron; and it consists in a certain novel construction and combination of devices, fully described hereinafter in connection with the accompanying drawings, and specifically pointed out in the appended claims.

In the drawings, Figure 1 is a side view of the improved drill. Fig. 2 is a central sectional view of the same. Fig. 3 is a detail view of the lower end of the shaft. Fig. 4 is a plan view of the socket. Fig. 5 is a detail view of the spring-pawl.

Referring by letter to the drawings, A designates the twisted or worm shaft, (which may be formed by twisting a square bar of metal,) the upper end of which is provided with a spindle, B, having a collar, C, at its lower end.

D represents the head or shield, to which is attached a depending socket or bearing, E, in which is swiveled the spindle B on the upper end of the shaft. A nut, F, is adjusted on the upper threaded extremity of the spindle and bears on a washer, f, whereby the shaft is allowed free rotary motion independent of the head or shield. The collar at the lower end of the spindle B bears against the lower end of the socket or bearing E.

The twisted or worm shaft is provided at its lower end with a rigid collar, G, below which is formed a round extension, H, having a peripheral groove, h, a short distance from its lower end, and I represents a ring, which fits snugly in the said groove flush with the surface of the extension and rotates freely therein. The upper end of the extension close under the collar G is provided with a ratchet, K.

L represents the bit socket or stock, in the lower end of which is fitted the bit M, of any suitable kind, and N represents a set-screw, 50 which is mounted in a threaded aperture in

the side of the socket or stock, and when tightened bears against the side of the bit to clamp it in place. The upper end of the socket or stock fits on the extension and bears against the lower side of the collar G, and the bore of the socket or stock is provided at the upper extremity with an enlargement, O, which fits around the ratchet, and in which is secured the spring-pawl P, which engages the ratchet. This pawl consists of a circular flat spring, p, 60 which extends around the bore of the socket or stock in its enlargement, and the enlarged head p' on the free end of the spring.

Screws Q Q are arranged in threaded apertures in the side of the socket or stock, and engage registering-depressions R R in the ring I, whereby the socket or stock rotates with the ring and is held thereby in position on the shaft. A set-screw, S, in the side of the socket or stock impinges at its inner end (when tightened) against the side of the extension between the ring and the ratchet and locks the socket or stock rigidly to the extension.

The operation of the improved drill is as follows: When the handle or sleeve T, which fits snugly on the shaft of the drill and is provided with a twisted or worm bore, is moved longitudinally along the shaft without being permitted to rotate in the hand, the latter is rotated alternately in opposite directions. 80 When the handle or sleeve is pushed toward the socket or stock, the pawl engages the ratchet and causes the socket or stock to rotate with the shaft in the direction in which a right-hand screw is tightened, thereby causing the bit to cut into the material which is being bored, and when the handle or sleeve is moved in the opposite direction the shaft is rotated in the opposite direction, the ratchet slips idly over the pawl, and the bit remains 90 stationary. Thus the bit is only rotated when the handle or sleeve is pushed downward. To withdraw screws, tighten the set-screw S, so as to clamp the bit socket or stock firmly to the shaft, then draw the handle or sleeve upward, or toward the head or shield, thereby rotating the socket or stock, and when at the upper end of the shaft release the handle or sleeve and allow it to slip idly to the lower end of the shaft.

The advantages of this invention—namely, simplicity, strength, and ease of operation—will be readily appreciated.

Having thus described the invention, I 5 claim—

1. In a drill, the combination of the twisted or worm shaft having a head or shield swiveled on its upper end, the handle or sleeve T, sliding on the shaft, the bit socket or stock 10 mounted on a cylindrical extension of the lower end of the shaft and provided with a spring-pawl engaging a ratchet on the said extension, and the set-screw S, mounted in a threaded aperture in the socket or stock and 15 engaging the extension to clamp the same rigidly together, substantially as specified.

2. In a drill, the combination of the twisted or worm shaft having a head swiveled on its upper end, the handle or sleeve sliding on the 20 shaft, the extension at the lower end of the shaft provided with a groove, the ring swiveled in the said groove, and the bit stock or socket mounted on the extension, secured by screws to the said ring, and provided with a 25 pawl engaging a ratchet on the extension, substantially as specified.

3. In a drill, the twisted or worm shaft provided at its lower end with a collar, G, and an extension, H, beyond the collar, provided with 30 a peripheral groove, h, the ring mounted in

the groove flush with the surface of the extension and provided with sockets R R, the bit socket or stock fitting on the extension and bearing against the lower side of the collar G, the screws passing through the socket or 35 stock and engaging the sockets R in the ring, the spring-pawl arranged in an enlargement of the bore of the socket or stock and engaging a peripheral ratchet on the extension under the collar G, and the handle or sleeve operating on the shaft, substantially as specified.

4. In a drill, the combination of the head or shield provided with a depending socket or bearing, E, the twisted or worm shaft provided at its upper end with a spindle, B, 45 mounted in the socket or bearing, and having a collar at its lower end which bears against the lower end of the socket or bearing, the nut engaging the upper end of the spindle, the bit socket or stock mounted on an extension 50 of the lower end of the shaft, and the pawl engaging a ratchet on the extension, substantially as specified.

In testimony that I claim the foregoing as my own I have hereto affixed my signature in 55 presence of two witnesses.

THORWALD GOSERND.

Witnesses:

A. D. THORP,
Wm. H. TIMLIN.

It is hereby certified that the name of the patentee in Letters Patent No. 394,169, granted December 11, 1888, for an improvement in "Drills," was erroneously written and printed "Thorwald Gosernd," whereas said name should have been written and printed *Thorwald Goserud*; and that said Letters Patent should be read with this correction therein that the same may conform to the record of the case in the Patent Office.

Signed, countersigned, and sealed this 8th day of January, A. D. 1889.

[SEAL.]

D. L. HAWKINS,
Assistant Secretary of the Interior.

Countersigned:

BENTON J. HALL,

Commissioner of Patents.
